RECLINING CHAIR AND LEG-REST

Fridtjof F. Schliephacke, Berlin-Schmargendorf, Germany, assignor to Anton Lorenz, Boynton Beach, Fla.

Filed May 6, 1959, Ser. No. 811,314

10 Claims. (Cl. 297—89)

The present invention relates generally to reclining chairs, and in particular to an improved leg-rest mounting and controlling arrangement for reclining chairs. This is a continuation-in-part of my earlier filed application Serial No. 689,729, filed October 11, 1957 and entitled "Leg-rest Mechanism for Reclining Article of Furniture," which earlier filed application is a continuation-in-part of my earlier filed application, Serial No. 651,709, filed April 9, 1957 and entitled "A reclining Article of Furniture," now U.S. Pat. No. 2,929,440 of March 22, 1960.

The well known reclining chair comprises a support, body-supporting means including a back-rest and seat movably mounted on a support and a leg-rest disposed beneath the seat and mounted for movement into an elevated leg-supporting position. Provision is made for moving the leg-rest from beneath the seat into the elevated leg-supporting position in response to the movement of the body-supporting means.

Broadly it is an object of the present invention to provide an improved leg-rest mounting and controlling arrangement for a reclining chair. Specifically, it is within the contemplation of the present invention to provide an improved and simplified leg-rest mounting and controlling arrangement which coordinates the elevation of the leg-rest to the movement of the body-supporting means. Advantageously, my improved leg-rest control finds application in reclining chairs of the type incorporating a movable back-rest and movable seat and reclining chairs of the type incorporating a unitary or rigid back-rest and seat.

In accordance with an illustrative embodiment demonstrating features of the present invention, my improved leg-rest mounting and controlling arrangement is employed in a reclining chair of the type which comprises a support and body-supporting means having a seat and back-rest movably mounted on the support. The arrangement comprises a leg-rest, a first double-arm lever pivotally mounted on the seat at a first pivotal mount, a second double arm lever pivotally mounted on one arm of the first lever at a second pivotal mount, means operatively connecting one arm of the second lever to the leg-rest, a constraining link pivotally connected to the support and to the other arm of the second lever, and actuating means operatively connected to the body-supporting means and to the other arm of the first lever. In response to movement of the body-supporting means relative to the support, the other arm of the first lever is swung through a forward arc whereby the one arm thereof, upon which the second double arm lever is pivotally mounted, swings through a rearward arc which is effective to elevate the leg-rest into various elevated leg-supporting positions in response to the movement of the body-supporting means relative to the support. In chairs of the type including a unitary or rigid body-supporting unit, the actuating means is controlled from any convenient point of such body-supporting unit; and in chairs of the type including a movable seat and movable back-rest the actuating means is conveniently controlled from the back-rest.

The above brief description, as well as further objects, features and advantages of the present invention will be more fully appreciated by reference to the following detailed description of presently preferred, but illustrative embodiments according to the present invention, when taken in conjunction with the accompanying drawings, wherein:

2

FIG. 1 is a side elevational view of an improved reclining chair demonstrating features of the present invention, the chair being shown in the upright or sitting position with the leg-rest in the stored or retracted position;

5 FIG. 2 is a side elevational view similar to FIG. 1, but showing the chair in a tilted position, with the leg-rest in an elevated leg-supporting position;

10 FIG. 3 is a side elevational view of a further embodiment of reclining chair according to the present invention, with the chair shown in the upright or sitting position and the leg-rest shown in the stored or retracted position;

15 FIG. 4 is a side elevational view similar to FIG. 3, but showing the reclining chair in a tilted resting position with the leg-rest in an elevated leg-supporting position;

20 FIG. 5 is a side elevational view of a further embodiment demonstrating further features of the present invention, with the chair shown in the upright or sitting position and with the leg-rest shown in the retracted or stored position;

25 FIG. 6 is a side elevational view similar to FIG. 5 but showing the chair in an intermediate tilted position, with the leg-rest in an elevated leg-supporting position;

30 FIG. 7 is a side elevational view similar to FIG. 5, but showing the chair in a fully reclined position;

FIG. 8 is a side elevational view of a further embodiment of reclining chair demonstrating still further features of the present invention, shown in the upright or sitting position with the leg-rest in an elevated leg-supporting position; and,

35 FIG. 9 is a side elevational view similar to FIG. 8, but showing the chair in a reclined position.

Referring now specifically to the drawings, there is shown in FIGS. 1 and 2 an improved reclining chair 10 demonstrating features of the present invention, generally designated by the reference numeral 10, which includes a support or frame 12 having opposite sides 14 interconnected by appropriate cross braces, the adjacent side of the chair having been removed for clarity to expose the operating linkages at such adjacent side of the chair. A rigid body-supporting unit 16 including a back-rest 18 and a seat 20 is mounted on support 12 for movement relative to the support into various tilted resting positions, such as shown in FIG. 2. Specifically, the body-supporting unit 16 is mounted on the support 12 by a four-bar supporting linkage which includes a front supporting link 22 and a rear supporting lever 24 having upwardly and downwardly extending arms 24a and 24b. The front supporting link has a pivotal mount 26 adjacent its lower end on the support and extends upwardly and forwardly, with a pivotal connection 28 at the upper end thereof to the seat 20 of the body-supporting unit 16. The rear supporting lever 24 has a pivotal mount 27 intermediate its ends on the support, with the arm 24a thereof extending upwardly and forwardly and having a pivotal connection 30 to the seat at a point spaced to the rear of the pivotal connection 28. The four-bar supporting linkage will be recognized as including as the stationary link thereof the portion of the support intermediate the pivotal mounts 26, 27 with the link 22, the portion of the seat 20 intermediate the pivotal connections 28, 30 and the arm 24a serving as the movable links thereof.

Disposed beneath the forward end of the seat is a leg-rest 32 which is movable from the stored or retracted position illustrated in FIG. 1 to the elevated leg-supporting position illustrated in FIG. 2. The leg-rest is mounted for movement relative to the support by a leg-rest mounting and control arrangement, generally designated by the reference numeral 34, which includes a first carrier or double-arm lever 36 having an upwardly directed first arm 36a and a downwardly directed second arm 36b. The double-arm lever 36 has a pivotal mount 38 on the

seat which pivotal mount is adapted to move in an upward and rearward arc in response to movement of the body-supporting unit 16 relative to the support 12. A second or mounting double-arm lever 40 is pivotally mounted on the first arm 36a of the lever 36 at a pivotal mount 42, with the second double-arm lever 40 having an upwardly and rearwardly projecting arm 40a and a downwardly projecting arm 40b. The pivotal mount 42 of the second double-arm lever 40 is movable relative to the support as a function of the movement of the body-supporting unit 16 in relation to the support and the turning movement of the lever 36 about pivotal mount 38 on the body-supporting unit 16.

The arm 40a of the mounting lever 40 is coupled to the support 12 by a constraining link 44 which has a stationary pivotal mount 46 on the support at its lower end and a pivotal connection 48 at its upper end to the arm 40a of the mounting lever 40 at a point spaced from the pivotal mount 42 thereof on the carrier lever 36.

The arm 40b of the mounting lever is coupled to the leg-rest 32 such that in response to turning movement of the mounting lever 40 about its pivotal mount 42 and swinging movement of the arm 40b through an upward and forward arc, the leg-rest 32 is moved to an elevated leg-supporting position as the body-supporting unit 16 moves to a tilted resting position. Specifically, a mounting arm or link 50 is provided which has a pivotal mount or connection 52 to the seat 20 at a point spaced forwardly of the pivotal mount 38 of the lever 36 on the seat. Connecting links 53, 54 are provided which are operatively connected to the mounting arm or link 50, to the leg-rest 32 and to the arm 40b for completing the leg-rest mounting arrangement. Specifically, the connecting link 53 has a pivotal connection 56 at its rearward end to the arm 40b of the mounting lever 40, has a pivotal connection 58 intermediate its ends to the mounting arm 50 at a cross-over point relative thereto, and has a pivotal connection 60 at its forward end to the leg-rest 32. The connecting link 54 has a pivotal connection 62 at its rearward end to the lower end of the mounting arm 50 and has a pivotal connection 64 at its forward end to the leg-rest at a point spaced from the pivotal connection 60. The leg-rest mounting linkage will be recognized as providing an extensible mount for the leg-rest wherein in response to turning movement of the lever 40b and displacement of the pivotal connection 56 towards the pivotal mount 52, there is a corresponding displacement of the pivotal connection 62 towards the connection 60 and extension and elevation of the leg-rest 32.

Actuating means are operatively connected to the body-supporting unit 16 and to the second arm 36b of the carrier lever 36 for swinging the arm 36b through a forward arc whereby the arm 36a thereof moves through a rearward arc, which movement occurs in response to rearward tilting movement of the body-supporting unit 16 such that the leg-rest 32 is elevated. In this embodiment, the actuating means includes the arm 24b of the supporting lever 24 which serves as a driver link coupled to the arm 36b by a connecting link 66 having a pivotal connection 68 at its rearward end to the driver link 24b and a pivotal connection 70 at its forward end to the arm 36b.

In order to facilitate a more thorough understanding of this embodiment of the invention, there will now be described a typical sequence of operations:

When the chair occupant is seated in the chair and leans against the back-rest 18 of the body-supporting unit 16, the body-supporting unit moves rearwardly and downwardly as a function of the design of the four-bar supporting linkage. As the arm 24a pivots through a rearward and downward arc about the pivotal mount 27, the arm 24b of the supporting lever 24 moves through a forward and upward arc imparting a forward thrust to the connecting link 66 which causes the first or mounting lever 36b to turn about its pivotal mount 38 on the seat, with the pivotal mount 38 moving through an upward

and rearward arc as a function of the design of the supporting linkage. The mounting lever 40 which is supported on the carrier lever 36 and constrained by the link 44 turns about its pivotal mount 42 on the arm 36a of the carrier lever 36 which causes the extension of the leg-rest 32. When the occupant desires to restore the chair to the upright sitting position the occupant merely presses against the leg-rest 32 which causes the chair to move from the tilted position shown in FIG. 2 to the upright sitting position of FIG. 1.

Referring now specifically to FIGS. 3 and 4, there is shown a further embodiment of reclining chair demonstrating features of the present invention, generally designated by the reference numeral 110, which includes a support or frame 112 having opposite sides 114 interconnected by appropriate cross braces, the adjacent side of the chair having been removed for clarity to expose the operating linkages at such adjacent side of the chair. A rigid body-supporting unit 116 including a back-rest 118 and a seat 120 is mounted on support 112 for movement relative to the support into various tilted back resting positions, such as shown in FIG. 4. Specifically, the body-supporting unit 116 is mounted on the support by a supporting linkage which includes a front supporting link 122 and a rear supporting lever 124 having upwardly and downwardly extending arms 124a and 124b. The front supporting link 122 has a pivotal mount 126 adjacent its lower end on the support and extends upwardly and rearwardly and has an operative connection to the seat 120 of the body-supporting unit 116 via the double-arm lever 136. The supporting lever 124 has a pivotal mount 127 intermediate its ends on the support with the arm 124a thereof extending upwardly and having a pivotal connection 130 to the seat adjacent the rear end thereof.

Disposed beneath the forward end of the seat is a leg-rest 32 which is movable from the stored or retracted position illustrated in FIG. 3 to the elevated leg-supporting position illustrated in FIG. 4. The leg-rest is mounted for movement relative to the support by leg-rest mounting and controlling arrangement, generally designated by the reference numeral 134, which includes the first or carrier double arm lever 136 having an upwardly directed first arm 136a and a downwardly directed second arm 136b. The double-arm lever 136 has a pivotal mount 138 on the seat which serves, via a pivotal connection 128 to the front supporting link 122, to complete the main supporting linkage. The pivotal mount is adapted to move in an upward and rearward arc in response to movement of the body supporting unit 116 relative to the support 112. A second or mounting double arm lever 140 is pivotally mounted on the first arm 136a of the lever 136 at a pivotal mount 142, with the second double-arm lever 140 having an upwardly and rearwardly projecting arm 140a and a downwardly projecting arm 140b. The pivotal mount 142 of the double arm mounting lever 140 is movable relative to the support as a function of the movement of the body-supporting unit 116 in relation to the support and the turning movement of the lever 136 about its pivotal mount 138 on the body-supporting unit 116.

The arm 140a of the mounting lever 140 is coupled to the support 112 by a constraining link 144 which has a stationary pivotal mount 146 on the support at its lower end and a pivotal connection 148 at its upper end to the arm 140a of the mounting lever 140 at a point spaced from the pivotal mount 142 thereof on the carrier lever 136. The arm 140b of the mounting lever 140 is coupled to the leg-rest 132 such that in response to turning movement of the mounting lever 140 about its pivotal mount 142 and swinging movement of the arm 140b through an upward and forward arc, the leg-rest 132 is moved to an elevated leg-supporting position. Specifically, a mounting arm or link 150 is provided which has a pivotal mount or connection 152 to the seat 120 at a point spaced forwardly of the pivotal mount 138 of

the lever 136 on the seat. Connecting links 153, 154 are provided which are operatively connected to the mounting arm or link 150 to the leg-rest 132 and to the arm 140b for completing the mounting arrangement. Specifically, the connecting link 153 has a pivotal connection 156 at its rearward end to the arm 140b of the mounting lever 140, has a pivotal connection 158 to the mounting arm 150 at a cross-over point relative thereto and has a pivotal connection 160 at its forward end to the leg-rest 132. The connecting link 154 has a pivotal connection 162 at its rearward end to the lower end of the mounting arm 150 and has a pivotal connection 164 at its forward end to the leg-rest 132 at a point spaced from the pivotal connection 160. The leg-rest mounting linkage will be recognized as providing an extensible mount for the leg-rest 132 wherein, in response to turning movement of the lever 140b and displacement to the pivotal connection 156 towards the pivotal mount 152, there is a corresponding displacement of the pivotal connection 162 towards the connection 160 and extension and elevation of the leg-rest 132.

Actuating means are operatively connected to the body-supporting unit 116 and to the second arm 136b of the carrier lever 136 for swinging the arm 136b through a forward arc whereby the arm 136a thereof moves through a rearward arc, which movement occurs in response to movement of the body-supporting unit 116. In this embodiment, the actuating means includes the arm 124b of the supporting lever 124 which serves as a driver link coupled to the arm 136b by a connecting link 166 having a pivotal connection 168 at its rearward end to the driver link 124b and a pivotal connection 170 at its forward end to the arm 136b.

In order to facilitate a more thorough understanding of this embodiment of the invention, there will now be described a typical sequence of operations:

When the chair occupant is seated in the chair and leans against the back-rest 118 of the body-supporting unit 116, the body-supporting unit moves rearwardly and downwardly as a function of the design of the supporting linkage, which linkage includes the portion of the support 112 intermediate the pivotal mounts 126, 127 as the stationary link thereof and the link 122, the arm 136 intermediate the pivots 128, 138, the seat intermediate the pivots 138, 130 and the arm 124a of the lever 124 as the movable links thereof. As the arm 124a pivots through a rearward and downward arc about the pivotal mount 127, the arm 124b of the supporting lever 124 moves through a forward and upward arc imparting a forward thrust to the connecting link 166 which causes the first or mounting lever 136b to turn about its pivotal mount 138 on the seat, with the pivotal mount 138 moving through an upward and rearward arc as a function of the design of the main supporting linkage. The mounting lever 140 which is supported on the carrier lever 136 and constrained by the link 144 turns about its pivotal mount 142 on the arm 136a of the carrier lever 136 which causes the extension of the leg-rest. When the occupant desires to restore the chair to the upright sitting position, the occupant merely presses against the leg-rest 132 which causes the chair to move from the tilted position shown in FIG. 4 to the upright sitting position of FIG. 3.

Referring now specifically to FIGS. 5 to 7 of the drawings, there is shown a further embodiment of reclining chair according to the present invention, generally designated by the reference numeral 210, which includes a support or frame 212 having opposite sides 214 interconnected by appropriate cross braces, the adjacent side of the chair having been removed for clarity to expose the operating linkages at such side of the chair.

In this embodiment, a body-supporting means including a back-rest 216 and a seat 218 are movably mounted on the support 212 for reclining an inclining movement respectively. Specifically, the back-rest is pivotally

mounted on the support at a back-rest pivot 220, with an extension 216a thereof depending below the back-rest pivot. The seat 218 has secured thereto rearwardly directed hangers 222 which mount the seat at a seat pivot 224 on the back-rest 216. The seat pivot 224 is spaced above the back-rest pivot 220 and is movable rearwardly and downwardly in an arc about the back-rest pivot 220 in response to chair movement, as will subsequently be described.

- 10   5   10   15   20   25   30   35   40   45   50   55   60   65   70   75
- Seat control means, generally designated by the reference numeral 226, are provided for inclining the seat 218 as a function of and in response to the reclining movement of the back-rest 216. Specifically, the seat control means includes a first or supporting link 228 having a pivotal mount 230 at its lower end on the support 212 and a second or seat control link 232 having a control pivot 234 on the seat 218. The first and second links 228 and 232 are disposed in converging relation, with the link 228 extending upwardly and rearwardly from its pivotal mount 230 and the link 232 extending rearwardly and downwardly from the control connection 234, with the adjacent rearward ends of the links 228, 232 being interconnected at a knee pivot 236. The links 228, 232 will be recognized as providing a toggle linkage pair, with the toggle action occurring as the knee pivot 236 moves towards an in-line position with respect to the pivots 230, 234 as more fully described in my copending application Serial No. 811,315, filed May 6, 1959 and entitled "Improved Reclining Chair and Seat Control." In response to reclining movement of the back-rest 216, the extension 216a via an actuating link 238 will be effective which has a pivotal connection 240 at its rearward end to the back-rest and a pivotal connection 242 at its forward end to the link 228 to cause the control pivot 234 to move rearwardly and upwardly, with the seat pivot 224 moving rearwardly and downwardly such that a compound inclination is imparted to the seat 218.

Disposed below the forward end of the seat 218 is a leg-rest 244 which is movable from a stored position (see FIG. 5) to various elevated leg-supporting positions (see FIGS. 6 and 7). The leg-rest is movably mounted by a leg-rest mounting and controlling arrangement, generally designated by the reference numeral 245, which includes an integral extension of the link 232, designated by the reference numeral 246, the oppositely directed arms 232, 246 constituting a double-arm carrier lever having the control pivot 234 as a pivotal mount therefor. A leg-rest mounting linkage is operatively connected to the arm or extension 246 and to the seat and includes a first link pair having first and second mounting links 248, 250 and a second link pair having first and second mounting links 252, 254. The first and second links 248, 250 of the first link pair have their adjacent ends pivotally connected at a pivot 256, while the first and second links 252, 254 of the second link pair have their adjacent ends pivotally connected at a pivot 258. The link 248 has a pivotal mount 260 on the seat adjacent the forward end thereof, while the link 252 has a pivotal mount 262 on the extension or rigid mounting arm 246 of the double arm carrier lever 246, 232. The link 250 has a pivotal connection 264 at its forward end to the leg rest 244, while the link 254 has a pivotal connection 266 at a point adjacent to and spaced rearwardly of its forward end to the leg-rest 244, with the pivotal connection 266 being spaced from the pivotal connection 264. The link pairs 248, 250 and 252, 254 are coordinated by a pivotal interconnection 265. The pivotal connection 264 is confined within a slot or guideway 268 formed in the leg-rest 244, with the pivotal connection 264 being connected via a control link 270 to the extension of the link 254 forwardly of the pivotal connection 266 at a further pivotal connection 272. The pivotal and slidably connection 264 of the leg-rest mounting linkage to the leg-rest 244 and the control link 270 and its pivotal connection 272 to the link 254 serves to properly position the leg-rest with

7
respect to the seat during reclining movement as disclosed and claimed in my copending application, Ser. No. 689,729, filed October 11, 1956 and entitled "Leg Rest Mechanism for Reclining Article of Furniture," now U.S. Pat. No. 2,929,440 of March 22, 1960.

The link 252 of the second link pair 252, 254 includes an integral projection or arm 253 extending upwardly from the pivotal amount 262, with the arms 252, 253 together constituting a double-arm mounting lever. A constraining link 274 has a pivotal connection 276 at its upper end to the arm 253 and a pivotal mount 278 at its lower end to the support 212. During reclining movement, the constraining link 274 causes the double-arm mounting lever 252, 253 of the leg-rest mounting linkage to turn on the pivotal mount 262, with the arm 253 moving in a clockwise direction about the pivotal mount 262 as may be appreciated by progressively inspecting FIGS. 5 to 7 inclusive.

In order to close the gap between the leg-rest 244 and the forward end of the seat 218, there is provided a filler board 280 which is secured by bolts, rivets or the like 282 to the link 254 intermediate the pivotal connection 266, 265. The filler board 280 moves to a position intermediate the seat 218 and the leg-rest 244 when the latter is moved to the leg-supporting position.

In order to facilitate a more thorough understanding of this embodiment of the invention, there will now be described a typical sequence of operations;

When the chair occupant is seated in the chair 210, and leans against the back-rest 216, the back-rest pivots around the back-rest pivot 220, with the depending extension 216a swinging through an upward and forward arc. The swinging movement of the extension 216a via the actuating or connecting link 238 causes the toggle link pair 228, 232 to straighten, with the knee pivot 236 moving toward a position in a line with the pivot 230, 234. The link 228 constitutes the driver of the toggle linkage mechanism and is constrained to move in a rotary path about the pivotal mount 230 to exert an axial force on the link 232 which constitutes the connecting link of the toggle linkage. The rotary motion of the driver under control of the back-rest extension 216a is such that the effective lever arm (which is the perpendicular distance from the line of action of the connecting link 232 to the center of rotation of the driver link 228) is less when the driver link is in the intermediate tilted position of FIG. 6 than in the initial sitting position of FIG. 5. The axial force produced in the connecting link 232 is transmitted to the seat 218 which is subjected to the toggle effect with this toggle effect occurring between the upright or sitting position illustrated in FIG. 5 and the intermediate tilted position shown in FIG. 6, with the intermediate tilted position occurring in advance of the final reclining position shown in FIG. 7. By employing this toggle effect, the seat 218 may be moved in relation to the back-rest in between the upright sitting position and the intermediate tilted position such that there is relatively no angular change in the relationship of the back-rest 216 and the seat 218, with the leg-rest 244 moving into and extended and elevated leg-supporting position. During the second phase of the reclining movement very little inclining movement is imparted to the seat by the seat control mechanism and accordingly the back-rest 216 increases its angle relative to the seat 218, as may be appreciated by progressively inspecting FIGS. 5 and 6. Insofar as the leg-rest control is concerned, the uniform motion imparted to the toggle linkage pair 228, 232 is effective during the first phase of the reclining movement to cause a relatively rapid elevation of the leg-rest until the pivots 230, 236, 234 of the toggle linkage approach the in-line or dead center position. Accordingly, when the reclining chair moves into the intermediate tilted position shown in FIG. 6, the leg-rest is substantially at its elevated leg-supporting position. As the in-line or dead center position of the toggle linkage is approached,

8
the continued uniform motion imparted to the driver link 228 manifests itself as a rapidly decreasing turning movement of the follower and accordingly the leg-rest 244, when once elevated, remains in a substantially fixed relation relative to the seat, with the angle between the seat 216 and the back-rest 218 opening up or increasing. In the final fully reclining position shown in FIG. 7 the leg-rest has moved up somewhat, with the seat and back-rest angle opening up to establish the requisite relationship therebetween for accommodating the chair occupant in a fully reclined position. When the chair occupant desires to restore the chair to the upright sitting position, the occupant merely presses against the leg-rest which causes the chair to move through the successive positions, such as illustrated in FIG. 6, to the upright sitting position of FIG. 5.

Referring now specifically to FIGS. 8 and 9 of the drawings, there is shown a further reclining chair 310 according to the present invention which includes a support or frame 312 having opposite sides 314 interconnected by appropriate cross braces, the adjacent side of the chair having been removed for clarity to expose the operating linkages at such side of the chair.

A body-supporting means including a back-rest 316 and a seat 318 are movably mounted on the support 312 for reclining an inclining movement respectively. Specifically, the back-rest is pivotally mounted on the support at a back-rest pivot 320, with an extension 316a thereof depending below the back-rest pivot 320. The seat 318 has secured thereto rearwardly directed hangers 322 which mount the seat at a seat pivot 324 on the back-rest 316. The seat pivot 324 is spaced above the back-rest pivot 320 and is movable rearwardly and downwardly in an arc about the back-rest pivot 320 in response to chair movement, as will subsequently be described.

Seat control means, generally designated by the reference numeral 326, are provided for inclining the seat 318 as a function of and in response to the reclining movement of the back-rest 316. Specifically, the seat control means includes a first or supporting link 328 having a pivotal mount 330 at its lower end on the support 312 and a second or seat control link 332 having a control pivot 334 on the seat 318. The lower end of the seat control link 332 is connected to the supporting link 328 at a pivot 336 spaced above the pivotal mount 330. The linkage pair 328, 332 is actuated from an actuating or connecting link 338 having a pivotal connection 340 at its rearward end to the depending extension 316a of the back-rest 316 at a point spaced below the back-rest pivot 320 and a pivotal connection at its forward end to the supporting link 328 coaxially with the pivot 336. Link 338, link 332 intermediate pivots 336, 334, the portion of the seat 318 intermediate the control pivot 334 and the seat pivot 324, the portion of the back-rest intermediate the seat pivot 324 and the back-rest pivot 320, all serve as movable links of the seat control means, with the portion of the support 312 intermediate the back-rest pivot 320 and the pivotal mount 330 serve as the stationary link thereof. In response to reclining movement of the back-rest 316, the extension 316a via the actuating link 338 will be effective to cause the pivot 334 to move rearwardly and upwardly, with the seat pivot 324 moving rearwardly and downwardly such that a compound inclination is imparted to the seat 318 in accordance with the proportions of the seat control linkage.

Disposed below the forward end of the seat 318 is a leg-rest 344 which is movable from a stored position (see FIG. 8) to various elevated leg-supporting positions (see FIG. 9). The leg-rest 344 is movably mounted by a leg-rest mounting and controlling arrangement, generally designated by the reference numeral 345. The leg-rest mounting and control arrangement 345 includes a leg-rest mounting linkage operatively connected to the double-arm carrier lever 346, 332 and the support 312 and in-

cludes a first link pair having first and second mounting links 348, 350 and a second link pair having first and second mounting links 352, 354. The first and second links 348, 350 of the first link pair have their adjacent ends pivotally connected at the pivot 356 while the first and second links 352, 354 of the second link pair have their adjacent ends pivotally connected at a pivot 358. The link 348 has a pivotal mount 360 on the support 312, while the link 352 has an arm or extension 353 to provide a double-arm mounting lever having a pivotal mount 362 on the arm 346 of the carrier lever 346, 332. The link 350 has a pivotal connection 364 at its forward end to the leg-rest 344, while the link 354 has a pivotal connection 366 at its forward end to the leg-rest 344, with the pivot 364 being confined in a slot 368 as aforesaid and with a control link 370 connected thereto and to the link 354 at a pivotal connection 372 forwardly of the pivotal connection 366. The link pairs 348, 350 and 352, 354 are coordinated at a pivotal interconnection 365, with the link 354 carrying a filler board 380.

The arm 353 is operatively connected to a constraining link 374 which has a pivotal connection 376 at its upper end to the arm 353 and a pivotal mount 378 at its lower end on the support 312. During reclining movement the constraining link 374 causes the arm 253 of the leg-rest mounting linkage to turn on the pivotal mount 362, with the arm 352 moving in a clockwise direction about the pivotal mount 362 and the pivotal mount translating upwardly and rearwardly as may be appreciated by progressively inspecting FIGS. 8 and 9.

In order to facilitate a more thorough understanding of this embodiment of the invention, there will now be described a typical sequence of operations:

When the chair occupant is seated in the chair 310, and leans against the back-rest 316, the back-rest pivots about the back-rest pivot 320, with the depending extension 316a swinging through an upward and forward arc. The swinging movement of the extension 316a via the actuating or connecting link 338 causes the supporting link 328 to swing about its pivotal mount 330 on the support 312. As the supporting link 328 swings in the counter clockwise direction, as shown in FIG. 9, the seat control link 332 is effective to cause the seat control pivot 334 to swing through an upward and rearward arc as the seat 318 moves rearwardly under the control of the back-rest, with the seat pivot 324 swinging through a rearward and downward arc about the back-rest pivot 320. Further, as the supporting link 328 swings through the forward arc, the leg-rest mounting linkage is actuated via the carrier lever 346, 332 and the mounting lever 352, 353 as aforesaid to move the leg-rest 344 to an elevated leg-supporting position.

A latitude of modification, change and substitution is intended in the foregoing disclosure and in some instances some features of the invention will be employed without a corresponding use of other features. Accordingly it is appropriate that the appended claims be construed broadly and in a manner consistent with the spirit and scope of the invention herein.

I claim:

1. In a reclining chair of the type including a support, body-supporting means including a seat and back-rest movably mounted on said support, the improvement comprising a leg-rest, a carrier lever pivotally mounted on said seat intermediate its ends and having two arms, linkage means mounting said leg-rest for movement from a stored position to an elevated leg-supporting position, said linkage means including a mounting lever pivotally supported intermediate its ends on one arm of said carrier lever, a constraining link, means pivotally connecting said constraining link to one arm of said mounting lever, means pivotally connecting the other arm of said mounting lever to said leg-rest, means pivotally connecting said constraining link to said support, and actuating means

operatively connected to said body-supporting means and to the other arm of said carrier lever.

2. In a reclining chair of the type including a support, body-supporting means including a seat and back-rest movably mounted on said support, the improvement comprising a leg-rest, a carrier lever pivotally mounted on said seat intermediate its ends and having upwardly and downwardly extending arms, linkage means mounting said leg-rest for movement from a stored position to an elevated leg-supporting position, said linkage means including a mounting lever pivotally supported intermediate its ends on said upwardly extending arm of said carrier lever, a constraining link, means pivotally connecting said constraining link to one arm of said mounting lever, means pivotally connecting said constraining link to said support, means pivotally connecting the other arm of said mounting lever to said leg-rest, and actuating means operatively connected to said body-supporting means and to said downwardly extending arm of said carrier lever.
3. In a reclining chair of the type including a support, body-supporting means including a seat and back-rest movably mounted on said support, the improvement comprising a leg-rest, a carrier link pivotally mounted on said seat intermediate its ends and having first and second arms, linkage means mounting said leg-rest for movement from a stored position to an elevated leg-supporting position, said linkage means including a mounting lever pivotally supported on said first arm of said carrier link, means pivotally connecting one arm of said mounting lever to said leg-rest, a constraining link, means pivotally connecting said constraining link to the other arm of said mounting lever, means pivotally connecting said constraining link to said support, and actuating means operatively connected to said body-supporting means and to said second arm of said carrier link.

4. In a reclining chair, a support, a body-supporting unit including a seat and back-rest rigid with each other and movably mounted on said support, a leg-rest, a carrier link pivotally mounted on said seat intermediate its ends and having first and second arms, linkage means mounting said leg-rest for movement from a stored position to an elevated leg-supporting position, said linkage means including a mounting lever pivotally supported on said first arm of said carrier link, means pivotally connecting one arm of said mounting lever to said leg-rest, a constraining link, means pivotally connecting said constraining link to the other arm of said mounting lever, means pivotally connecting said constraining link to said support, and actuating means operatively connected to said body-supporting unit and to said second arm of said carrier link.

5. In a reclining chair, a support, body-supporting means having a seat and back-rest movably mounted on said support, a leg-rest, a first double-arm lever pivotally mounted on said seat at a first pivotal mount and having two arms, a second double-arm lever pivotally mounted on one arm of said first lever at a second pivotal mount and having first and second arms, a constraining link pivotally connected to said support and to one arm of said second lever at a point spaced from said second pivotal mount, a mounting arm, means pivotally mounting said arm on said chair at a point spaced forwardly of said first and second pivotal mounts, linkage means operatively connected to said mounting arm, said leg-rest and the other arm of said second lever, and actuating means operatively connected to said body-supporting means and to the other arm of said first lever for swinging said other arm of said first lever through a forward arc whereby said one arm thereof moves through a rearward arc to elevate said leg-rest.

6. An improved leg-rest mounting and controlling arrangement for a reclining chair of the type including a support and body-supporting means having a seat and back-rest movably mounted on said support, said arrangement comprising a leg-rest, a first double-arm lever pivot-

ally mounted on said seat at a first pivotal mount, a second double-arm lever pivotally mounted on one arm of said first lever at a second pivotal mount, means operatively connecting one arm of said second lever to said leg-rest, a constraining link pivotally connected to said support and to the other arm of said second lever at a pivotal connection spaced from said second pivotal mount, and actuating means operatively connected to said body-supporting means and to the other arm of said first lever for swinging said other arm through a forward arc whereby said one arm thereof moves through a rearward arc to elevate said leg-rest.

7. An improved leg-rest mounting and controlling arrangement for a reclining chair of the type including a support and body-supporting means having a seat and back-rest movably mounted on said support, said arrangement comprising a leg-rest, a first double-arm lever pivotally mounted on said seat at a first pivotal mount and having an upwardly directed first arm and a downwardly directed second arm, a second double-arm lever pivotally mounted on said first arm of said first lever at a second pivotal mount, means operatively connecting one arm of said second lever to said leg-rest, a constraining link pivotally connected to said support and to the other arm of said second lever at a pivotal connection spaced from said second pivotal mount, and actuating means operatively connected to said body-supporting means and to said second arm of said first lever for swinging said second arm through a forward arc whereby said first arm thereof moves through a rearward arc to elevate said leg-rest.

8. An improved leg-rest mounting and controlling arrangement for a reclining chair of the type including support and body-supporting means having a seat and back-rest movably mounted on said support, said arrangement comprising a leg-rest, a first double-arm lever pivotally mounted on said seat at a first pivotal mount and having an upwardly directed first arm and a downwardly directed second arm, a second double-arm lever pivotally mounted on said first arm of said first lever at a second pivotal mount and having an upwardly directed first arm and a downwardly directed second arm, a constraining link pivotally connected to said support and to said first arm of said second lever at a point spaced from said second pivotal mount, a mounting arm, means pivotally mounting said arm on said chair at a point spaced forwardly of said first and second pivotal mounts, linkage means operatively connected to said mounting arm, said leg-rest and second arm of said second lever, and actuating means operatively connected to said body-supporting means and to said second arm of said first lever for swinging said second arm of said first lever through a forward arc whereby said first arm thereof moves through a rearward arc to elevate said leg-rest.

9. An improved leg-rest mounting and controlling arrangement for a reclining chair of the type including a support and body-supporting means having a seat and

back-rest movably mounted on said support, said arrangement comprising a leg-rest, a first double-arm lever pivotally mounted on said seat at a first pivotal mount and having an upwardly directed first arm and a downwardly directed second arm, a second double-arm lever pivotally mounted on said first arm of said first lever at a second pivotal mount and having an upwardly directed first arm and a downwardly directed second arm, a constraining link pivotally connected to said support and to said first arm of said second lever at a point spaced from said second pivotal mount, a mounting arm, means pivotally mounting said arm on said seat at a point spaced forwardly of said first and second pivotal mounts, linkage means operatively connected to said mounting arm, said leg-rest and second arm of second lever, and actuating means operatively connected to said body-supporting means and to said second arm of said first lever for swinging said second arm of said first lever through a forward arc whereby said first arm thereof moves through a rearward arc to elevate said leg-rest.

10. An improved leg-rest mounting and controlling arrangement for a reclining chair of the type including a support and body-supporting means having a seat and back-rest movably mounted on said support, said arrangement comprising a leg-rest, a first double-arm lever pivotally mounted on said seat at a first pivotal mount and having an upwardly directed first arm and a downwardly directed second arm, a second double-arm lever pivotally mounted on said first arm of said first lever at a second pivotal mount and having an upwardly directed first arm and a downwardly directed second arm, a constraining link pivotally connected to said support and to said first arm of said second lever at a point spaced from said second pivotal mount, a mounting arm, means pivotally mounting said arm on said support at a point spaced forwardly of said first and second pivotal mounts, linkage means operatively connected to said mounting arm, said leg-rest and second arm of said second lever, and actuating means operatively connected to said body-supporting means and to said second arm of said first lever for swinging said second arm of said first lever through a forward arc whereby said first arm thereof moves through a rearward arc to elevate said leg-rest.
